ATTORNEYS.

UNITED STATES PATENT OFFICE.

EUGEN PRESTINARI, OF IRVINGTON, NEW JERSEY, ASSIGNOR TO GEMEX COMPANY OF NEWARK, NEW JERSEY, A CORPORATION OF NEW JERSEY.

BRACELET.

Application filed January 8, 1927. Serial No. 159,875.

- This invention relates to a construction of bracelet chain of the extendible type; and the object of this invention is to provide a bracelet having a plurality of similar extendible units connected together in a series to form a chain, each of the units being detachable one from the other to vary the working length of the bracelet and adapt it for different sized wrists of different persons.
- 5 A further object of the invention is to provide a construction having top and side walls on two telescoping relatively slideable links of each unit whereby a chain made up of these units has an attractive appearance.
- 10 A further object of the invention is to provide between two telescopically arranged boxes means to serve in cooperation with one of the boxes to detachably connect the units together.
- 15 A still further object of this invention is the provision of an I-shaped connecting member having one of its heads detachable for the mounting of a spring to be guided thereby and to operate between the boxes.
- 20 With these and other objects in view, the invention consists of certain novel features of construction, as will be more fully described, and particularly pointed out in the appended claims.
- 25 In the accompanying drawings:
- Figure 1 is a perspective view of a series of units of the bracelet chain connected together.
- Figure 2 is a perspective view of a blank of the outer box link or casing.
- 30 Figure 3 is a perspective view showing this blank folded to form the outer box or casing.
- Figure 4 is a perspective view of the inner box.
- 35 Figure 5 is a perspective view of one of the parts of the separable connecting member.
- Figure 6 is a view of the other part of the connecting member.
- 40 Figure 7 is a perspective view of the connecting member with the spring for acting between the box mounted thereon.
- 45 Figure 8 is a perspective view with the bottom portion of the outer box or casing removed and showing the arrangement of the part with the inner box extended from the outer box placing the resilient means under tension.
- 50 Figure 9 is a sectional top view of the two units connected together.
- Figure 10 is a sectional side view of the 55 same.
- Figure 11 is a sectional view on line 11—11 of Figure 10.
- Figure 12 is a side elevation partly broken away illustrating the relative position of the 60 units for disconnecting one unit from the other.
- It is found in the practical construction and operation of extendible bracelets and chains, of advantage to provide a series of connected 65 like units which may be detached one from the other by manual manipulation and which provide a broad top wall having side walls or both of two relatively slideable links to hide the working parts of the bracelet, to receive 70 ornamentation and to enhance the appearance thereof. It is also found desirable in such a construction to connect the inner and outer telescoping boxes of this form with a separate connecting member to make the construction strong which connecting member also may be utilized in cooperation with one of the boxes for detachably connecting the links together; and the following is a detailed 75 description of the present embodiment of this 80 invention and showing one construction of bracelet by which these advantageous results may be obtained.
- With reference to the drawings, 10 designates the inner box which is preferably 85 formed of sheet metal bent into the form illustrated having a top wall 11, side walls 12, end walls 13 and hinge connecting fingers 14. Within this inner box the connecting member 15 is mounted having a shank 16 with an 90 integral head 17 and a detachable head 18 which has a tongue 20 to fit within the groove 21 in the shank to removably connect the same thereto. The shank portion 16 of the connecting member extends through the 95 opening 22 in the end wall 13 of the box and a spring 23 surrounds the shank 16 to abut against the head 18 and the wall 13 tending to move the inner box relative to the connecting member to contracting position. An outer 100 box or casing 24 is positioned about the inner box 10 and connecting member 15 to house the same and has a top wall 25, bottom wall 26 and side walls 27 from which extend ears 28 having openings 29 to receive the reduced 105 trunnions 30 on the head 17 of the connecting member which protuberances are suitably secured to the ears 28 by riveting over or the

like which serves to support the side walls 27 of the casing and prevent separation thereof to open the seam 31 at the bottom.

The detachable connection between the units is secured by fingers 14 on the inner box engaging the head 17 of the connecting member when the units are in substantially right angular position, as illustrated in Figure 12, it being necessary to slightly extend the bracelet units in order that their detachable connection may be accomplished thus preventing accidental detachment as the springs are tending to hold the units in their contracted position at all times.

15 A lip 32 is provided at the top end of the outer box or casing which extends over the inner box at its connection to effectively hide the joint from view.

From the foregoing it will be seen that I 20 have provided a simple yet effective and strong construction of bracelet which may receive ornamentation to make the same attractive in appearance and which may be easily assembled and the units detached one from 25 the other when desirable.

The foregoing description is directed solely towards the construction illustrated, but I desire it to be understood that I reserve the privilege of resorting to all the mechanical 30 changes to which the device is susceptible, the invention being defined and limited only by the terms of the appended claims.

I claim:

1. An extendible bracelet chain comprising a series of connected units, each unit having an outer box, an inner box slidable relative thereto, a connecting member having a laterally extending portion fixedly secured to one of said boxes adjacent one end thereof 35 and slidable relative to the other box, a spring acting between said member and the box slidable relative thereto, and a hook carried by the last mentioned of said boxes of one unit for detachably engaging said laterally extending portion of the connecting member of the next unit.

2. An extendible bracelet construction comprising a series of connected units detachably hinged together, each unit comprising 40 an outer casing, an inner box therein slid-

able relative to said casing, a connecting member slidable relative to said inner box, and having a laterally extending portion fixed to said casing, and a hook on one end of said inner box for engaging the laterally extending portion of said connecting member, said hook being shaped to be detachable therefrom by a movement of the hook carrying part at right angles to the bracelet length. 55

3. An extendible bracelet construction 60 comprising a series of connected units detachably hinged together, each unit comprising an outer casing having top and side walls, an inner box therein having an end wall and side walls and slidable relative to said casing, a connecting member fixed to the side walls of said casing and extending through said end wall intermediate its side walls, an abutment on said connecting member within said box, a spring acting between 65 said abutment and end wall to house said box in said casing and a hook on said box for detachably connecting the box of one unit to the member of the next unit. 70

4. In an extendible bracelet, a series of 75 connected units each comprising an outer box, an inner box therein, an I-shaped connecting member having heads connected by a shank, means for fixing one of the heads of said member to said outer box, and a spring 80 embracing the shank of said member and engaging the opposite head of said member and a portion of the other of said boxes whereby a yielding sliding movement of the boxes is 85 permitted, and a hook on one of said boxes for detachably engaging the head of the member fixed to another of said boxes. 90

5. In an extendible bracelet, a series of connected units each comprising an outer box, 95 an inner box therein, an I-shaped connecting member having heads connected by a shank, means for detachably connecting one of the heads to said shank, a spring surrounding said shank and acting between a portion of the inner box and one of said heads and means for securing the other head to the other of said boxes.

In testimony whereof I affix my signature.

EUGEN PRESTINARI.
